UNITED STATES PATENT OFFICE.

DECATUR E. ARNOLD, OF JOHNSON CITY, TENNESSEE.

HACK SAW.

Application filed September 26, 1921. Serial No. 503,846.

To all whom it may concern:

Be it known that I, DECATUR E. ARNOLD, a citizen of the United States, residing at Johnson City, in the county of Washington 5 and State of Tennessee, have invented new and useful Improvements in Hack Saws, of which the following is a specification.

The principal object of this invention is to provide means for supporting a motor 10 driven hack saw upon the vise which holds the work piece.

Another object of the invention is to provide means for adjusting the parts so that the saw will engage the desired part of the 15 work piece so as to cut a piece off the same or to make kerfs therein.

Another object of the invention is to provide means whereby the saw parts may be adjusted in relation to the vise.

20 A further object of the invention is to provide means whereby the work piece can be held at any desired angle in the vise and still be operated upon by the saw.

This invention also consists in certain 25 other features of construction and in the combination and arrangement of the several parts, to be hereinafter fully described, illustrated in the accompanying drawings and specifically pointed out in the appended 30 claims.

In describing my invention in detail, reference will be had to the accompanying drawings wherein like characters denote like or corresponding parts throughout the several views, and in which:

Figure 1 is a plan view of the invention.

Figure 2 is a side view thereof.

Figure 3 is a section on line 3—3 of Figure 1.

40 Figure 4 is a section on line 4—4 of Figure 1.

The remaining figures are detail views.

In these views 1 indicates the stationary jaw of the vise and B the movable jaw there- 45 of, said jaws being connected together by the screw shaft 3 which is provided with the handle 4, these parts being of the usual or any desired construction. The front jaw is provided with an extension 5 and a base 6 is 50 adjustably clamped to the extension by means of the L-shaped combination bolt and clip 7. This bolt passes through an opening in the base where it receives a nut 8 and the horizontal part of the clip is connected with 55 a depending part of the base by a bolt 10 and nut 11. A thumb screw 12, passing

through the clip and engaging the extension, serves as a transverse clamp. Thus the base is adjustably mounted on the extension of the vise. The base is provided in its upper 60 face with a dove-tail groove 13 which receives a dove-tail projection 14 on a table 15 so that the table is slidable transversely on the base. This table supports the motor 16 and the bearings 17. A shaft 18 is rotatably 65 mounted in the bearings and said shaft is driven from the motor shaft through the worm gearing 19. A crank 20 is connected with the outer end of the shaft. A substantially L-shaped arm 21 is hingedly connect- 70 ed with the shaft by having a bearing 22 at the end of the horizontal limb receiving the shaft and held against one of the bearings of the shaft by the collar 23. The limb of this arm curves outwardly and has secured 75 thereto the horizontally arranged supporting bar 24 for the saw frame 25. The horizontal limb of the L-shaped arm rests upon the table when in its lowest position. The saw frame 25 is provided with the guides 26 80 which engage the supporting bar 24 and said frame is connected with the crank 20 by means of the link 27. Thus when the crank shaft is revolved the saw frame will be reciprocated upon the supporting bar 24. The 85 saw 28 is connected at one end to the saw frame by means of the T-shaped clip 29 engaging the forked end of the saw frame and held in position by the bolt 30 and the other end of the saw is connected with the frame 90 by means of the forked clip 31 engaging the notched end 32 of the frame and held thereon by the cam lever 33.

It will thus be seen that the saw parts are mounted upon the vise which holds the 95 work piece A so that this piece can be cut by the saw while held in the vise. This piece can be held horizontally as shown in Figures 1 and 2 or at an angle as shown at 8' in Figure 4. The supporting base can 100 be adjusted longitudinally upon the vise ex- tension while the table can be adjusted laterally upon the base so that the saw can be properly positioned to make the desired cut in the work piece. By having the L- 105 shaped arm pivoted to the crank shaft the saw frame and its support can be raised and lowered to engage the work piece.

It is thought from the foregoing description that the advantages and novel fea- 110 tures of my invention will be readily apparent.

I desire it to be understood that I may make changes in the construction and in the combination and arrangement of the several parts, provided that such changes 5 fall within the scope of the appended claims.

What I claim is:—

1. In combination with a holding vise provided with an extension, a supporting base connected with the extension, a table 10 mounted upon the base, a motor carried by the table, a movably mounted supporting member connected with the table, a hack saw frame slidably supported by said member and means for reciprocating the frame 15 from the motor.
2. In combination with a holding vise having an extension, a base adjustably supported thereon, a table supported by the base, a motor carried by the table, a supporting member swingingly connected with the table, a hack saw frame slidably mounted on the member and means for reciprocating the frame from the motor.
3. In combination with a holding vise 25 having an extension, a base adjustably supported on the extension, a table slidably mounted on the base in a lateral direction, a motor carried by the table, a supporting member swingingly attached to the table, 30 a hack saw frame slidably supported by

said member and means for reciprocating the frame from the motor.

4. In combination with a holding vise having an extension, a base adjustably mounted on said extension, a table slidable 35 laterally on said base, a crank shaft journaled on the table, a motor mounted on the table and geared to said shaft, a supporting member pivotally connected with the shaft, a hack saw frame slidably supported on said 40 member and means for connecting the frame with the crank of the shaft.

5. In combination with a holding vise having an extension, a base adjustably supported thereon, a table slidably mounted 45 on the base in a lateral direction, a crank shaft journaled on the table, a motor carried by the table and geared to the crank shaft, an L-shaped arm having one end pivoted on the shaft with its horizontal arm 50 engaging the table when in lowered position, a horizontal supporting bar connected with the upper end of said arm, a saw frame slidably mounted on said supporting bar and a link connecting said frame with 55 the crank of the shaft.

In testimony whereof I affix my signature:

DECATUR E. ARNOLD.
